UNITED STATES PATENT OFFICE

AUBREY C. NOWLIN, OF BEGGS, OKLAHOMA, ASSIGNOR OF FOUR-TENTHS TO A. C. FLIEG, FOURTEEN ONE-HUNDREDTHS TO J. G. SALES, BOTH OF OKMULGEE COUNTY, OKLAHOMA, AND ONE ONE-HUNDREDTH TO NATHAN B. TOWNSEND

NUT OPENING AND PICKING MACHINE

Application filed January 16, 1929. Serial No. 332,827.

This invention relates to nut opening and picking machines for use in connection with pecans and the like.

The invention forming the subject of this application contemplates a machine having means to cut the shell of a pecan or the like into a number of sections and to subsequently bring about the complete separation of the sections thus formed to permit of the recovery 10 of the kernel of the nut without damage thereto.

A further object of the invention is to provide a machine of the character specified having means by which pecans or the like are fed to the machine in rapid order and are conducted therethrough for successive action by the cutting and stripping elements by which the expeditious removal of the kernels from the shells is accomplished, it being 20 noted in this connection that the machine is adapted for use in connection with pecans of various sizes within commercial limits and is intended to remove the kernels intact from the shells thereof so that the market value 25 of the pecans will not be impaired.

Other objects and advantages will be apparent during the course of the following description.

In the accompanying drawings forming a 30 part of this application and in which like numerals are employed to designate like parts throughout the same.

Figure 1 is a side elevation of the machine.

Figure 2 is a fragmentary plan view illustrating an ejecting and feeding mechanism by which the pecans or the like are presented in succession to a plurality of conveyors for movement through the machine.

Figure 3 is a detailed longitudinal sectional view taken on line 4—4 of Figure 2,

Figure 4 is a detailed vertical transverse sectional view taken on line 4—4 of Figure 2,

Figure 5 is a vertical transverse sectional view taken on line 5—5 of Figure 1, the view being taken in the direction indicated by the arrows,

Figure 6 is a detailed sectional view illustrating a yieldable bearing support embodied 50 in the invention.

Figure 7 is a perspective of a bearing embodied in the invention,

Figure 8 is a detailed sectional view illustrating the means by which the pivoted dogs carried by the several conveyor chains are embedded in the shell of the pecan,

Figure 9 is a perspective illustrating the sprocket wheel shown in Figure 8,

Figure 10 is a sectional view taken on line 10—10 of Figure 1, the view being taken in 60 the direction indicated by the arrows,

Figure 11 is a detailed longitudinal view illustrating the guiding means by which the active runs of the conveyors are held in line,

Figure 12 is a detailed transverse sectional view taken on line 12—12 of Figure 1,

Figure 13 is a fragmentary side elevation of one of the conveyor chains, parts being broken away,

Figure 14 is a fragmentary plan view illustrating the construction of the conveyor chains,

Figure 15 is a sectional perspective of a piston embodied in the invention,

Figure 16 is a front view illustrating a stripper plate by which the kernel of the nut is removed intact from the section to which it may remain attached subsequent to the separation of the shell into sections,

Figure 17 is an edge view of the stripper plate and associated elements,

Figure 18 is an elevation of a cutting mechanism by which the shell of the pecan is cut lengthwise,

Figure 19 is an elevation taken at right angles to Figure 18,

In the drawings wherein for the purpose of illustration is shown a preferred embodiment of the invention the numeral 20 designates a base upon which standards 21, 22 and 23 are mounted in spaced relation.

As illustrated in Figure 2, the standards 23 carry a drive shaft 24 upon which a suitable power transmitting element such as a spur gear 26 is keyed or otherwise connected. Obviously, the power transmitting element 26 may have connection with a suitable source of power not shown. The drive shaft 24 is provided with a crank to which a pitman rod 27 is connected and the forward portion of the 100

pitman rod is shown to have connection with a piston or ejector 28.

Attention is now invited to Figure 3 which illustrates that the piston 28 intersects a discharge opening in the bottom of a hopper 29 so that when the piston is fully retracted a pecan may drop to a position immediately in front of the piston for subsequent movement into engagement with the conveyors to be described.

Jiggers or straightening devices 31 are mounted for reciprocation at opposite sides of the piston 28 and have connection at the rear ends thereof with pitman rods 32, the pitman rods being connected in turn to the gears 34. By way of illustration, the gears 34 are shown to have connection with a second set of gears 36 keyed or otherwise secured to the drive shaft 24. Since the gears 34 are substantially less in diameter than the diameters of the gears 36, the jiggers or straightening devices 31 will be operated at a speed substantially greater than that of the piston 28.

Figure 2 illustrates that the arrangement of the pitman rods 32 and the means by which the same are connected to the gears 34 is such that when one jigger is advanced the other jigger occupies the rearmost position.

By this arrangement, the pecans are straightened and are guided into the space immediately in advance of the piston 28. In further alluding to this feature attention is invited to Figures 3 and 4 which illustrate that the upper surfaces of the jiggers or straightening devices are serrated and are beveled downward in direction of the piston 28 so that the lowermost pecan in the hopper 29 is directed into the discharge socket defined by the opposed sides of the jiggers and the bottom wall of the hopper. Incidentally, the bottom wall of the hopper functions as a support for the jiggers 31 and the piston 28.

The serrations in the upper sides of the jiggers 31 will agitate the pecans within the hopper 29 to avoid congestion of the same at the outlet point. Figure 1 illustrates that the standards 21 support the hopper 29 while the standards 22 support the gears 34 and the shafts upon which the same are mounted.

Coming now to the means by which the pecans are conducted through the machine so that the shells thereof may be cut lengthwise at points approximately 90 degrees apart, attention is invited to Figure 5 which illustrates that there are four separate jointly operated conveyor chains approximately 90 degrees apart and having active runs extending in spaced parallel relation so that the dogs carried thereby may have secure engagement with the four sections of the pecan.

The conveyor chains are generally designated by the numerals 35 and are trained about sprocket wheels 37. Specifically, each

wheel 37 is in the nature of two laterally spaced disks having the peripheral portions thereof notched for the reception of the extended terminals of the connecting pins 38 of the sprocket chains. Figure 13 admirably illustrates that the pins 38 carry dogs 39 and 40 having teeth 42 and 44 respectively adapted to be embedded in the shells of the pecans to securely engage the same. The teeth 42 and 44 carried by each link of the chain constitute a pair for engagement with the pecan at longitudinally spaced points and since the chains are located approximately 90 degrees apart the pecans will be engaged by the aforesaid pairs of teeth at four points so that the same may be later cut lengthwise into quarters as will be later brought out.

The sprocket wheels at the inlet end of the machine are provided with hubs upon which L-shaped arms 50 are mounted. The arms 50 are mounted between the laterally spaced disks forming each sprocket wheel and are provided with rollers 52 located in the path of travel of and adapted to be engaged by the outer edges of the dogs 39 and 40 to force the teeth 42 and 44 into the shells of the pecans. Figure 13 illustrates that the outer edges of the dogs 39 and 40 are cam like so that upon being engaged with the rollers 52 the teeth 42 and 44 will be embedded in the shell of the pecan. Incidentally, the four sets of teeth are forced more or less simultaneously into the shell of the pecan to bring about the uniform engagement of the teeth with the pecan shell.

The dogs 39 and 40 are shown in Figure 13 to be provided with arcuate slots 54 receiving pins 55 by which the pivotal movement of the dogs is restricted to operative limits.

With the pecan thus engaged by the four sets of teeth, the same is conducted through the machine and is successively presented to the cutting action of a plurality of disk saws 56. Like the conveyor chains, the disk saws are located about 90 degrees apart and are located one in advance of the other or are staggered at spaced points in the line of travel of the pecans so that the various longitudinal cuts in the shell of the pecan are made separately. The general arrangement of the saws is illustrated in Figure 1 while the specific construction of the saws is illustrated in Figures 18 and 19, the latter illustrating that the saws are mounted on spindles 58 having worm gears 59 engaged by worms 60 on the forward portions of motion transmitting shafts 62. The outer portions of the shafts 62 are provided with suitable motion transmitting means 64 for operative connection with longitudinal shafts 66 extending from a convenient source of power. The shafts 62 and the spindles 58 are carried by arms 68 having the outer portions thereof bifurcated to straddle the motion transmitting means 64 and at the same time to define ears that

115

120

125

130

135

are swivelly connected to the brackets 70 by fastening devices 72. By this arrangement, the saws are rotated for cutting through the shell of the pecan and as clearly shown in Figures 1, 18 and 19, the cutting depths of the saws are limited by more or less semicircular guards 76.

The guards 76 are located on opposite sides of the disks 56 and are adapted for engagement with the outer surfaces of the pecan shells so that the cutting depths of the saws are limited. This confines the cut to the shell and leaves the kernel intact for subsequent recovery.

Attention is invited to the fact that the ends of the guard recede appreciably to bring about relatively deep cuts at the ends of the pecan shells to assure the complete division of the pecan shell into four sections. In this connection it might be noted that the shells of pecans are known to be substantially thicker at the ends than at the intermediate portions. The relatively deep cuts at the ends of the pecan bring about what might be said to be the complete shattering of the ends of the pecan so that the removal of the sections is greatly simplified. The saws are urged into pressure contact with the pecan shell by springs 79.

When a quartered pecan shell and the enclosed kernel reach the outlet end of the machine the links connected to the pecan shell will ride about the sprocket wheels and thus expose the kernel of the pecan.

Possibly the kernel of the pecan will drop away from all of the sections of the shell, but in case it does not it will be conveyed into engagement with a stripper plate 80 and will be freed to drop into a suitable receiver. The stripper plate is shown in Figure 16 to be provided with intersecting slots 82 receiving portions of the sprocket wheels and the sprocket chains and closely embracing these parts for engagement with the kernel of the pecan.

The quartered sections of the pecan shell will remain attached to the dogs until engaged with the stripper arms 86 carried by the frame 88 of the machine. Figure 1 illustrates that the stripper arms 86 are provided with V-shaped notches, the walls of which are adapted for engagement with the shells of the pecans to completely detach the same from the dogs 39 and 40.

As previously suggested the machine is adaptable for use in connection with pecans of various sizes without previous grading of the pecans and without special adjustment of the machine. In this connection attention is invited to Figure 5 which illustrates that the sprocket wheels 37 have connection with shafts 90 in which conventional or other universal joints 160 are interposed. The universal joints 160 are located at opposite sides 65 of the sprocket wheels 37 to permit of the

radial separation of the sprocket wheels and the chains carried thereby without disturbing the driving engagement between the bevelled gears 92 on the outer portions of the shafts. Slip joints 91 provide for the variations in the lengths of the shafts 90. This construction permits of the radial movement of the conveyor chains to accommodate pecans of various sizes.

Figure 6 illustrates that the shafts 90 are carried by bearing blocks 94 urged inward by springs 96. The blocks 94 are carried by the frame of the machine and are intended to permit of the random admission of pecans without strain on the sprocket wheels and the chains.

The active runs of the conveyor chains are embraced by separate channeled members which as suggested in Figure 11 embody pivotally and slidably connected links 98. The ends of the links are overlapped and are connected for sliding and pivotal movement by pivot pins 99. The sections or links 98 are held in line with each other and are urged inward by springs 100, the ends of which are attached to lugs 101 carried by the end portions of the links or sections 98. The ends of the channel members embodying the links 98 have connection with attaching arms 104, the outer portions of which are recessed as suggested in Figures 6 and 12 for the partial reception of the bearing blocks 94. Thus it is, that the guides for the active runs of the conveyors are mounted for radial movement in unison with the active runs of the conveyor.

The piston illustrated in detail in Figure 15 and designated by the numeral 28 comprises inner and outer interfitting sections, the outer section being urged to an extreme forward position in the inner section by an expansion spring 176. The movement of the inner section of the piston 28 on the inner section thereof is limited by a pin and slot connection 178. The construction illustrated in Figure 15 provides for the ejection of pecans of various sizes and also assures the absorption of shock incident to the successive feeding of the pecans into the carriers therefor.

In summarizing the operation of the machine, it might be pointed out that a quantity of the pecans of random sizes are introduced into the hopper 29 and are allowed to drop singly into the space between the jiggers 31 so that when the piston 28 is subsequently advanced the pecans will be supplied to the pecan passage defined by the four more or less parallel uniformly spaced active runs of the conveyors. Upon the introduction of the pecans lineally into the space between the conveyors, the dogs 39 and 40 are moved by the rollers 52 in the direction of the pecans so that the teeth 42 and 44 are embedded in the pecans. With the pecans thus securely en-

gaged by the four conveyors the same are presented to the longitudinally spaced saws or other cutting devices so that the shells of the pecans are divided into segments or quarters.

5 When the pecans reach the outlet end of the machine the links engaged with the shells move outwardly to bring about the complete separation of the shell segments previously formed whereby the kernels of the pecans are left attached to one of the segments or are allowed to drop into a suitable receiver. As brought out in the specific description of the machine, the kernels which remain attached to the sections of the pecans are removed by 10 the action of the stripper plate 80 and finally the sections of the shells are disengaged from the conveyors by the stripper arms 86. Attention might be directed to the fact that the pins 54 clearly shown in Figure 13 limit the 15 pivotal movement of the dogs 39 and 40 so that when the dogs are returned to the inlet end of the machine the teeth 42 and 44 thereof will be in position for proper engagement with the shells of the newly admitted pecans.

20 25 It is obvious that a machine constructed in accordance with this invention is capable of use in connection with nuts other than pecans and that the invention is capable of a wide variety of mechanical expressions. Therefore it is to be understood that the form of the invention herewith shown and described is to be taken merely as a preferred example of the same and that such minor changes in the arrangement and construction of parts may 30 35 be made as will remain within the spirit of the invention and the scope of what is claimed.

Having thus described the invention what is claimed is:

40 45 1. A nut opening and picking machine comprising a plurality of conveyors having links provided between the ends thereof with separate opposed dogs adapted for secure engagement with nuts to carry the same through the machine, a cutting device in the path of travel of the nuts and having means to limit the penetrating depth of the same, a yieldable support for said cutting device, and a stripper to remove the shells of the nuts from engagement with the conveyor.

50 55 2. In a machine of the character specified, a plurality of radially arranged conveyors having active runs in substantially spaced parallel relation to define a passage for the movement of nuts, yieldable supporting means for certain of the conveyors, a plurality of longitudinally spaced cutting devices between the ends of the active runs of the conveyors, and yieldable supports for said cutting devices.

60 65 3. In a machine of the character specified, a plurality of radially arranged conveyors having active runs in substantially spaced parallel relation to define a passage for the movement of nuts, yieldable supporting means for

certain of the conveyors, a plurality of longitudinally spaced cutting devices between the ends of the active runs of the conveyors, yieldable supports for said cutting devices, said conveyors being provided with teeth for penetrating engagement with the shells of nuts, and stripping means to remove the shells of the nuts from engagement with the conveyors.

70 75 80 85 90 95 100 105 110 115 120 125 130 4. In a machine of the character specified, a plurality of conveyors having active runs in substantially spaced parallel relation to define a passage for the movement of nuts, yieldable supporting means for certain of the conveyors, a plurality of longitudinally spaced cutting devices between the ends of the active runs of the conveyors, yieldable supports for said cutting devices, said conveyors being provided with teeth for penetrating engagement with the shells of nuts, stripping means to remove the shells of the nuts from engagement with the conveyors, and guiding devices for the active runs of the conveyors.

10 15 20 25 30 35 40 45 50 55 60 65 70 75 80 85 90 95 100 105 110 115 120 125 130 5. In a machine of the character specified, a plurality of radially arranged conveyors having active runs in substantially spaced parallel relation to define a passage for the movement of nuts, yieldable supporting means for certain of the conveyors, a plurality of longitudinally spaced cutting devices between the ends of the active runs of the conveyors, yieldable supports for said cutting devices, said conveyors being provided with teeth for penetrating engagement with the shells of nuts, and stripping means to remove the shells of the nuts from engagement with the conveyors, guiding devices for the active runs of the conveyors, yieldable supporting means for said conveyors and having means connecting said conveyor guides with the yieldable supporting means for the conveyors whereby the conveyors and the guiding means thereof move in unison, and means to feed nuts linearly to the passage defined by the active runs of the conveyors.

10 15 20 25 30 35 40 45 50 55 60 65 70 75 80 85 90 95 100 105 110 115 120 125 130 6. In a nut opening and picking machine, a plurality of separate conveyors having pivoted dogs provided with teeth adaptable for penetrating engagement with the shells of nuts, cutting devices between the ends of the conveyors and adaptable for cutting engagement with the shells of nuts engaged by said teeth and having means to force said teeth into biting engagement with opposite sides of nuts, and stripping means to detach the shells of the nuts from engagement with said teeth.

7. In a nut opening and picking machine, a plurality of radially arranged endless conveyors having active runs in substantially spaced parallel relation to define a nut passage having inlet and outlet ends, longitudinally spaced cutting devices extending into said passage to divide the shells of the nuts into segments, a stripper to remove the meat

of the nuts from engagement with the segments formed by the cutting devices and comprising a plate having intersecting slots receiving the conveyors, portions of the plate being in the path of travel of and adapted to be engaged by the meat of the nuts to detach the same intact from the segments.

8. In a machine of the character specified, a conveyor consisting of a plurality of links having pivoted dogs provided with teeth adapted to be embedded in the shells of nuts, means limiting the pivotal movement of said dogs, and means in the path of travel of and adapted to engage the dogs to move the teeth thereof into the shells of nuts.

15 9. In a machine of the character specified, a plurality of conveyor chains having pivoted dogs provided with teeth, sprocket wheels supporting the chains, brackets associated with said sprocket wheels and having means in the path of travel of and adapted to engage said dogs to urge the teeth thereof into penetrating engagement with the shells of nuts, and cutting devices for engaging the shells of the nuts.

20 10. In a machine for opening nuts, a saw, a guard associated with the saw and having the ends thereof receded allowing the saw to cut deeper at the ends of the nuts, and a movable support for the saw.

25 11. In a machine for opening and picking nuts, a plurality of endless conveyors having active runs arranged in opposed relation to define a passage having inlet and outlet ends, cutting devices extending between said active runs for engagement with the shells of nuts, and a stripper to remove the meat of the nuts from engagement with the segments formed by the cutting devices and comprising a plate having openings receiving the conveyor, the ends of said openings being in the path of travel of and adapted to be engaged by the meat of the nut to detach the same intact from the segments.

30 12. In a machine for opening and picking nuts, a plurality of endless conveyors having active runs in cooperating relation to define a passage having inlet and outlet ends, cutting devices for engagement with said nuts, a stripper to remove the meat of the nut from engagement with the segments formed by the cutting devices and embodying a plate having slots receiving said conveyor, portions of the plate being in the path of travel of and adapted to be engaged by the meat of the nut to detach the same intact from the segments, and means to remove the segments of the nut shells from the conveyor subsequent to the removal of the meat from the segments of the shells.

35 13. In a machine for deshelling nuts, a plurality of link chain conveyors, sprockets supporting the link chain conveyors, said link chain conveyors being provided with teeth adapted to engage opposite sides of nuts to hold the same in place, cutting devices in the

path of travel of the nuts carried by said conveyors, channel shaped guides for the active runs of the conveyors, and a common yieldable supporting means for said guides and said sprocket wheels.

40 In testimony whereof I affix my signature.
AUBREY C. NOWLIN.
